BROOM AND STAFF HOLDER

Floyd E. Bateman, Loomis, Calif.

Application July 10, 1935, Serial No. 30,686

2 Claims. (Cl. 24—249)

The invention relates to an improved device for use in holding suspended brooms, mops, and other handled tools, fishing rods and the like, and has for one of its objects the provision of a holder that is reasonable in cost of manufacture, that may be secured to a wall or other upright support, and that will frictionally engage the handle or staff to securely hold it in suspended position, and that is so constructed that the handle or staff may be inserted and secured in position by one hand.

A further object of the invention is the provision of a broom and staff holder that will effectively hold the broom or staff without marring it, and is provided with means for holding the broom or staff by its own weight.

The invention will be described in detail hereinafter and will be found illustrated in the accompanying drawing, in which

Figure 1 is a side view in elevation of the improved broom and staff holder showing a broom in suspended position,

Figure 2 is a front view of the broom and staff holder on an enlarged scale,

Figure 3 is a sectional view on a vertical plane indicated by the line 3—3 of Figure 2,

Figure 4 is a view on a horizontal plane indicated by the line 4—4 of Figure 3, and

Figure 5 is a sectional detail on a plane indicated by the line 5—5 of Figure 3.

Referring to the drawing in which similar reference characters are used to designate corresponding parts throughout the several views, the improved broom or staff holder is preferably made of sheet metal and has a substantially U-shaped base member 10 having its sides cut out as shown at 11 and the cut out portions bent laterally of the U-shaped member providing tongues 12 having keyhole slots 13 therein to receive the stems of driven fastenings 14. The bight portion 15 of the U-shaped member 10 is also provided with a keyhole slot 16 to receive the stem of another driven fastening 14. By this construction it will be apparent that the device may be removed and replaced readily.

The side walls 17 of the U-shaped member 10 are provided with angular shaped notches 18, the upper edges of the notches 19 being substantially at right angles to the front edges 20 of the U-shaped member 10, while the lower edges of the notches 18 incline forwardly and

downwardly relatively to the edges 19, at an acute angle thereto.

Below the edges 21 of the recesses 18 is secured a substantially semicylindrical member 22, bridging the space between the side walls 17, and secured thereto in any suitable manner. Mounted in the recesses 18 is a circular disk or plate 23 having an opening 24, and provided with a radial extension 25 terminating in a cross bar 26, having reduced extensions 27 engaging in openings 28 in the sides 17, and forming trunnions pivoting the plate for vertical swinging movement in the recesses 18.

As shown in Figure 1, a handle or staff A is held in clamped position by engaging the upper end of the handle or staff in the opening 24 and is clamped therein by engagement against the semicylindrical insert 22, it being apparent that as the upper edges 19 of the recesses 18 will limit the upward swinging of the disk or plate 23 to a horizontal position that the end of the handle or staff may be readily inserted in the opening 24 by pushing the handle or staff against the disk or plate 23 with one hand, while by lifting the disk or plate when the broom handle or staff is in position to a horizontal position, the handle or staff will drop from engagement in the opening 24, being released from engagement with the semicylindrical member 22.

What is claimed is:

1. A broom and staff holder having spaced side walls provided with oppositely disposed V-shaped notches, a concave wall connecting said side walls below said notches, a disk pivotally mounted between said side walls and movable in said notches, said disk having an opening to receive a broom handle or staff, the edges of said notches limiting the pivotal movement of said disk.

2. A broom and staff holder, comprising a U-shaped base member having side walls provided with V-shaped notches, a concave member connecting the extremities of the side walls below the notches, a disk pivotally mounted between the side walls and movable in said notches, said disk having an opening therein to receive a broom handle or staff, the edges of said notches limiting the pivotal movement of said disk, and means to secure said base member to an upright support.
